UNITED STATES PATENT OFFICE

ALBERT HUGUENIN, OF PARIS, FRANCE

APPARATUS FOR DISTANT HYDRAULIC CONTROL

Application filed June 5, 1929, Serial No. 368,723, and in France October 18, 1928.

In the modern industrial plants which are constantly on the increase, and are also becoming more complicated, a great need is felt for a central control of all the elements or devices serving to determine the operation of the general installation. Such central control is now carried out by mechanical, electric and hydraulic means, and also by compressed air, but the control becomes difficult to realize when the controlled devices must also be held fast in their given position against all movement.

Electric control would seem the best adapted for this purpose, but this has a great defect consisting in the fact that the circuit must be frequently broken during all the different movements, thus causing sparking and also a great wear of the parts, and due to such wear, the controls lose their accuracy, and hence will after a time be put entirely out of use.

The present invention relates to an exclusively hydraulic method which is most accurate and affords the control of the different actuated devices at all distances and positions with reference to the central controlling apparatus, while at the same time the actuated devices are held fast against all motion, but without the plant and apparatus being submitted to such an amount of wear which will affect the accuracy of the control of the proper working of the plant for an indefinite length of time. For this purpose, in fact, a liquid under pressure proves a most effective power transmitting agent and can be used by reason of its incompressibility as the substance by which the several actuated devices are held against motion, whatever be the form of construction in use.

The said plants comprise a great number of different controls, according to modern practice in manufacturing plants. For this reason, the cost of installation of the central controlling apparatus must be reduced to a minimum, and herein the hydraulic system offers the additional advantage of a grouping of the controlled devices in lots, and for instance by lots of ten or twelve units.

The appended drawings show by way of example an embodiment of the invention.

Fig. 1 is a diagrammatic view of the controlling apparatus.

Fig. 2 is a vertical section of a distributor already illustrated in Fig. 1, but in another position.

Figs. 3 and 4 illustrate in vertical section a slide valve already shown in Fig. 1, but in two different positions.

a is an oil tank, oil being preferably employed as the liquid, since it is a lubricant and will not attack the metals. The said tank or casing contains the essential parts of the device and its top part *b* forms the controlling table or board; *c* is a geared pump, suitably driven, using preferably an electric motor. It is provided with a suction pipe *d* and a delivery pipe *e*. On the suction pipe is mounted a gate valve *f* controlling the feed of the pump. Since the pump operates constantly and at uniform speed, its feed will also be constant, and this supply is to be furnished with the minimum resistance, and thus circulated directly into the casing *a* so as to reduce the power used when the controlling parts of the installation are inoperative, or otherwise this power would be excessive. The pump thus operates during the period in which no effective control takes place, at a very low pressure, so as to reduce the power to the minimum, but as soon as this source of power is connected to a servo-motor having a certain resistance, the pressure at the feeding end of the pump now instantly rises to the value required to overcome this resistance. It is thus evident that in these conditions almost the whole amount of the oil will be withdrawn by the pump from the bottom of the casing *a* and will return directly to the latter, while a certain part of this oil will only be circulated in the servo-motors when these latter are put under control.

The essential object of the apparatus according to the invention is attained in the following manner.

The feeding or delivery pipe *e* of the pump leads to the distributor *g* and particularly to its annular conduit *h*, in which, in the present example the oil circulates according to the signs $\oplus$ $\ominus$ in the clockwise direc-

tion when the apparatus is viewed from the top. The distributor g is shown in Figure 1 in the inoperative position, and thus the piston i opens the ports k of a sleeve l , so that 5 the oil from the pump will be discharged according to the arrows, Figure 1, through the orifices m , and descends directly into the tank a .

In fact, the piston i is connected by its 10 rod n to a controlling piston o which slides in the cylinder g^2 fixed to the distributor g and is urged by a spring p against a stop q which is adjustable and is mounted on a cover r .

15 When no servo-motor is acted upon by a control, the circulation of the oil under pressure takes place from the delivery orifice of the pump through the said annular conduit h and the ports $k-m$, thence descending directly to the bottom of the casing a . This 20 throttling of the oil is so small that it has practically no effect upon its temperature.

The controlling device itself consists of a 25 valve chest s containing a double piston forming a slide valve t , also the oil feeding conduits u and connecting conduits $v-w$ leading to the servo-motors, which may be of the piston type x , or of the type comprising two gear wheels y , and it is obvious that one 30 slide valve controls only one servo-motor.

The slide valve as shown in Figure 1 is 35 provided with hand control, actuated by a lever z which is mounted on a toothed wheel a' . The valve can be moved vertically in either direction by a rack b' which is formed 40 on the extended rod of the valve. A locking bolt device (not shown) serves to hold the lever in the vertical position when out of use, and thus holds the valve i in its middle 45 position (Fig. 1) corresponding to a free connection between the space comprised between the two parts of the piston valve, and the intake of the oil under pressure supplied by the pipe u , the pressure herein being the same as the pressure in the annular conduit h of the distributor g .

The two conduits v and w leading to the servo-motors are entirely closed off by the 50 two parts of the piston valve; the two ports of a small conduit c' connect the part below the piston o to the said valve chest. The two ports $d'-e'$ of said conduit c' are also closed by the two portions of the piston when in the middle position (Fig. 1). The 55 operative covering of these two portions of the piston with reference to the two ports d' and e' is however much smaller than that of the conduits $v-w$ connecting the valve to the servo-motors.

60 In this manner, when the slide valve is in the inoperative position it entirely closes the conduit c' leading to the distributor on the one hand and the two conduits v and w leading from the valve to the servo-motors on the 65 other hand. Thus the servo-motors, whether

of the type x or y , are held fast in their position and will resist certain external efforts which may act upon them, but not be able to change their position. The pressure which may prevail in the conduits v and w will in fact depend only upon these external efforts which tend to act upon the servo-motors, and if there are no such efforts, there will be no pressure. It is thus observed that the great majority of the conduits, which are in fact situated between the valves and the servo-motor will not be subjected to pressure in the inoperative position, and pressure will only occur when one of the servo-motors is operated.

As concerns this operation, reference is made to Figures 2, 3 and 4. Fig. 2 shows the new position assumed during the operation by the movable part $i-n-o$ of the distributor. Figs. 3 and 4 show the two characteristic 81 positions of the movable piston valve t .

If for instance the said lever z is used to raise the valve t , the first effect of this motion is shown in Figure 3, and after a very short stroke, the port d' is opened, so that the oil under pressure from the conduit u will circulate according to the arrow (Fig. 3), thus acting upon the lower face of the distributor piston o , which now rises, compressing its spring p . As soon as the piston i commences 95 to cover the ports k , the oil which is driven forward by the pump will have no outlet, and thus the output pressure will at once rise and it rapidly increases, thus increasing the speed of the ascending stroke of the piston o until this piston is arrested by the stop f' at the end of the cylinder.

As it continues to rise, the double piston t finally attains the position shown in Figure 4, and it will be noted that while leaving the 10 port d' constantly open and thus maintaining the movable portion of the distributor g in its upper position, the oil under pressure supplied by the pump can be discharged through the conduit v which thus furnishes oil under 11 pressure to the servo-motor while at the same time the conduit w discharges its oil and also the oil of the servo-motor (according to the arrows) directly into the casing a , thus serving as the return conduit.

The element or apparatus to be controlled by the servo-motor x or y will thus move through a distance proportional to the time in which the double piston t is held in the position of Figure 4, for as soon as the lever z is used to lower the movable portion of the slide valve, that is, the double piston t , the operations take place in the order shown in Figs. 4, 3 and 1, and as soon as the position of Figure 3 is again attained, all motion 120 of the servo-motor x or y will have ceased, this servo-motor being again held against all motion; in the position of Figure 1 the port d' will be again closed, thus cutting off the delivery pressure at the lower portion of the 125

piston o of the distributer g whose movable portion will return to the position of Figure 1 by the action of its spring p ; the oil below the piston can escape through the conduit g' in the direction of the arrow, Figure 2, and this oil returns directly into the tank a . When the movable portion i in o of said distributer begins to uncover the ports k of the sleeve l , the oil discharged by the pump begins to leave the circular conduit h in a direct manner, according to the arrows, Figure 1, and to enter the said tank. This evacuation of the oil will be again complete, and the pressure is a minimum in the pump as soon as the said movable portion i in o of the distributer has returned to the position of Figure 1.

Obviously, the conduit g' , which is permanently in communication with the bottom r of the distributer, has a small section, in such manner that when the whole output of the pump circulates through the port d' (now open) and comes below the piston o , the resulting loss of oil will be negligible and the operations will occur exactly as described.

The operations herein specified take place when the piston t is raised by the lever z , that is, when the lever is moved (Fig. 1) to the right and is returned to the middle position, and in this case the conduit v becomes the supply conduit and the conduit w serves for the discharge. However, if the lever is moved to the left (Fig. 1) and then returned to the middle position, the same operation will take place, but herein the port e' connects the feed of the pump to the portion below the piston o of the distributer, and the conduit w becomes the supply conduit and the conduit v serves for the discharge, this discharge of oil takes place directly into the tank a through the apertures h' in the direction of the arrow (Fig. 1). All other factors being equal, what will take place is the inverse motion of the controlling element or device operated by the servo-motor of the type x or y .

Obviously, one distributer is provided for a whole series of slide valves, and this number is limited in practice only by the degree of fluid tightness of the double pistons t . In Fig. 1, a single slide valve can be seen, because the other slide valves are similar and exactly located behind the first one. The same conduit u supplies all these slide valves through a transverse header u' , and all the slide valves feed the same cylinder g^2 through a transverse header c^2 . The plant according to the invention is thus distinguished by the use of a very limited number of parts, and is therefore of an inexpensive nature.

Should in any case the control of a servo-motor be carried out to an excessive degree, so that for either direction of movement of the servo-motor the piston t is held in the

position of Figure 4 beyond the end of the stroke of the servo-motor, a safety exit must be provided for the oil supplied by the pump, in order to avoid all damage. For this purpose, the distributer comprises a safety valve i' which is connected directly by the pipe k' to the annular conduit h , and the operating pressure on the valve is adjustable, since its spring l' is adjustable by the nut m' . The oil from said valve flows through the orifice n' and thus returns directly to the tank a .

The arrangement herein represented is given solely by way of example, and the same principle may be embodied in other forms of construction.

Claims:

1. In a distant hydraulic control, the combination of a vessel for a liquid, a pump for sucking and delivering the said liquid, a servo-motor adapted to be actuated in either direction by the liquid delivered by the said pump, a slide valve actuated by hand and serving to control the admission and escape of the liquid delivered by the pump, respectively to both sides of the servo-motor a distributer causing the delivery conduit of the pump to alternatively communicate with the said vessel and with the slide valve, and control means for actuating the said distributer, these means being actuated in one direction by a spring, and, in the opposite direction, by the liquid delivered by the pump, the said slide valve being adapted to admit the liquid delivered by the pump into the said control means a short time before admitting it into the servo-motor, substantially as illustrated and described and for the purpose set forth.

2. In a distant hydraulic control, the combination of a vessel for a liquid, a pump adapted to suck the liquid in this vessel, a distributer comprising a chamber receiving the liquid delivered by the pump and having outlet openings for allowing the said liquid to return within the said vessel, a movable obturating member adapted to close the said openings, a cylinder, a piston sliding in said cylinder and adapted to move the said obturating member and a spring pushing said piston, a servo-motor, a distributing cylinder, a slide-valve in said distributing cylinder, this cylinder having orifices respectively connected, on the one hand to the said chamber receiving the liquid delivered, on the other hand, to the said cylinder having the spring actuated piston, on the other hand to the liquid vessel, and finally to the said servo-motor, this slide valve being adapted to be actuated by hand and to control the said orifices, the latter being so arranged that, in its position of rest, the said slide valve obturates the communications of the said distributing cylinder with the said spring actuated piston and with the said servo-motor that in one of its working positions it allows the said chamber receiving the liquid delivered to commu-

nicate with the said cylinder having a spring
actuated piston, and that in a more advanced
working position, it allows, on the one hand,
the said chamber to communicate with one
of the sides of the servo-motor and, on the
other hand, the other side of the servo-motor
to communicate with the said exhaust orifices
connected to the liquid vessel.

In testimony whereof I have hereunto af-
10. fixed my signature.
